UNITED STATES PATENT OFFICE

164,736

ADVERTISING DEVICE

Edward Hardin Sanders, San Francisco, Calif.

Application October 8, 1948, Serial No. 149,040

Term of patent 3½ years

(Cl. D1—2)

To all whom it may concern:

Be it known that I, Edward H. Sanders, a citizen of the United States, residing at 1045 Sansom Street, in the city and county of San Francisco and State of California, have invented a new, original, and ornamental Design for an Advertising Device, of which the following is a specification, reference being had to the accompanying drawing, forming part thereof.

Fig. 1 is a side elevational view of an advertising device, showing my new design. The opposite side not shown is identical in appearance to the side shown.

Fig. 2 is an end elevational view of the advertising device shown in Fig. 1. The opposite end not shown is substantially identical in appearance to the end shown.

Fig. 3 is a top plan view of the advertising device shown in Fig. 1.

Fig. 4 is a bottom plan view of the advertising device shown in Fig. 1.

I claim:

The ornamental design for an advertising device, as shown and described.

EDWARD HARDIN SANDERS.
